FLOOR FAN HOUSING

William P. Ayers, 390 E. St. Charles Road,
St. Charles, Ill. 60148

Filed May 11, 1966, Ser. No. 2,250

Term of patent 14 years

(Cl. D62—4)

Fig. 1

Fig. 2

Fig. 3

FIG. 1 is a top plan view of a floor fan housing;
FIG. 2 is a front side elevational view of the housing;
FIG. 3 is a side elevational view of the housing.

The bottom, backside and opposite side views are mirror images of the views shown in the figures, respectively.

I claim:

The ornamental design for a floor fan housing, as shown and described.
